ARTICLE-CONVEYING MECHANISM

Lawrence J. Saladin, Chicago, Ill., assignor to
Wm. Wrigley Jr. Company, Chicago, Ill., a corporation of Delaware

Original application July 28, 1941, Serial No.
404,260. Divided and this application June 1,
1942, Serial No. 445,297

15 Claims. (Cl. 198—24)

This invention relates to a novel and improved article conveying mechanism and consists of the matters hereinafter described and more particularly pointed out in the appended claims.

The object of the invention is to provide a conveyor by means of which elongated pieces of gum or the like are intermittently fed endwise from a hopper to a casing whence, and by means contained in said casing, the pieces are fed laterally flatwise to a wrapping machine whereby the sticks are successively wrapped.

The advantages of the invention will be obvious to those familiar with the art.

This application is a division of an application heretofore filed by me July 28, 1941, Serial No. 404,260, now Patent No. 2,306,191, dated December 22, 1942, for improvements in Package wrapping machine.

In the drawings:

Figure 1 is a view representing a front elevation shown partially in section of the novel stick conveying and transfer mechanism, together with a wrapping drum to which the sticks are delivered.

Figure 2 is a partial end view on an enlarged scale of the feed end of the machine looked at from a plane indicated by the line 2—2 of Figure 1.

Figure 3 is a partial vertical sectional view in a plane indicated by the line 3—3 of Figure 7, the scale being the same as that of Figure 2.

Figure 4 is a sectional view like unto Figure 3, with the parts in different position.

Figure 5 is a view representing a side elevation, partly in section, of the conveyor and transfer mechanism, and a stick-wrapping mechanism to which it delivers the sticks to be wrapped.

Figure 6 is a view similar to Figure 5 showing parts thereof in a different position.

Figure 7 is a horizontal plan section on an enlarged scale of the parts shown in Figure 1.

Referring now to that embodiment of the invention illustrated in the drawings: 20 indicates the machine frame upon which the various parts now to be described are mounted. The pieces of gum or the like to be wrapped are fed endwise, one by one, into a vertical tubular channel member 23. The channel 23 opens at its bottom end into a flat circular casing 24 (see Figures 2, 3, 4 and 5) fixed to the frame in a vertical plane extending at right angles to the plane of the sticks fed through said channel member. From said casing 24 and by mechanism contained therein, the pieces are fed laterally, flatwise (to

the left as shown in the drawings) towards a piece-wrapping machine to which, as illustrated in this case, the pieces are to be transferred.

In the casing 24 and concentric therewith is mounted a rotary feed member 25. It comprises laterally spaced discs 25a, 25a (see Figure 5) with an interposed spacing disc 25b of smaller diameter to which they are fixed. Said rotor is keyed to a horizontal shaft 26 having suitable bearing 27 in the frame. Its spaced discs 25a, 25a are each provided with a plurality (four in this instance) of like, equally spaced, radially disposed arms 28 with arcuate fingers 29 radially spaced from the disc and extending in the direction in which the rotor is designed to rotate, as indicated by the arrow in Figure 3. The fingers 29 of one of said discs 25a have lateral projections 29a which extend through a circular space or slot 30 between a circular plate 31, which forms a vertical wall of the casing 24 and the circular wall 24a of the casing 24.

A spring controlled vertical gate 32 is pivoted within the casing 24 by a horizontal pin 32a located forwardly of the vertical path of discharge of the pieces A from the channel 23 into the casing 24. Said gate normally stands as a continuation of the forward wall of the said channel (see Figure 2). The pin 32a is rotatively mounted in a cover 24b hinged at 24c to the casing 24 (see Figures 2, 3 and 5). Said pin 32a extends beyond the plane of the wall plate 31 of the casing as shown in Figure 2. There it has fixed to it a trip arm 32b, disposed to swing in a vertical plane and depending into the path of travel of the lateral projections 29a of the fingers 29.

At points spaced in the direction of rotation of the rotor 25 from the said lateral projections 29a are alike, equally spaced pockets 33 formed in its spaced discs 25a. Said pockets are inclined rearwardly to a radius of the rotor with respect to the direction of its rotation and are adapted to receive the pieces of gum or the like when a pocket comes into alignment below the channel 23. In the casing 24, in vertical alignment below the channel 23 and in the space between the rotor discs 25a, 25a is a horizontal shelf 34 fixed to the casing 24 (see Figures 3, 4 and 5).

As will be seen in Figures 2 and 3, each of the arcuate fingers 29 define the outer side of an arcuate slot 29b, which is formed in the rotary discs 25a, 25a, and extends circumferentially from the following side edge of each pocket 33. The purpose of these slots will hereinafter more fully appear.

The operation of the mechanism in the casing

24 is as follows: By gravity the pieces A are delivered in succession endwise through the chute 23 to the casing 24. The lowermost piece A is caught in the pocket 33 directly below the chute 23. The gate 32, providing the bottom part of the forward wall 23^a of said chute, guides said piece into said pocket. This position of the parts is illustrated in dotted lines in Figure 2. In said position, an offset 29^a of a finger 29 is near to the end of the trigger 32^b.

In the next operative movement of the rotor 25 the said offset 29^a strikes the trigger 32^b and swings the gate away from the piece A in the pocket 33, permitting said piece to be carried on by the rotor. At the same time the next succeeding piece above is engaged by and rides upon the fingers 29 and arms 28 until the next succeeding pocket 33 is brought to position below the chute 23. Thereupon said piece is guided into said pocket. To facilitate and guide the movement of the piece A into said pocket the arm 28 has a heel 28^x which is curved inwardly toward said pocket in manner to reduce the shock of the drop of said piece into the pocket. In the meantime the spring-controlled gate 32 has returned to its position of forming the forward wall of the chute. In this movement of the rotor the piece deposited in the pocket 33 is delivered to the shelf 34 upon which it rests until it is discharged therefrom, as will be now described.

From the shelf 34 in the casing 24 the pieces A are fed intermittently sidewise and transversely of said casing by a horizontally reciprocable plunger 35 to a wrapping drum 36 (see Figure 5). To this end, the casing 24 is provided with horizontal aligned openings in the plane of the shelf 34—an opening 34^a for the entrance of said plunger 35 and an outlet opening 34^b for the discharge of a piece A. The wrapping drum 36 is of familiar construction, with pockets 37 equally spaced about its periphery. It is intermittently operated in timed relation to the operation of the said feed rotor 25 and the plunger 35, to bring one of its pockets 37 into horizontal alignment with the shelf 34 and the outlet opening 34^b of the casing 24, to receive a piece A when it is propelled by said plunger 35 into said pocket 37. After the retraction of said plunger has commenced, the rotor 25 is again operated to deposit another piece A on the shelf 34, after which the first operation is repeated.

The purpose of the circumferentially disposed slots 29^b adjacent the following side edges of pockets 33 will now be apparent. The arrangement shown permits the rotor 25 to be started while the plunger 35 is still being withdrawn from pocket 33 after a piece has been propelled from the latter. By avoiding interference between the plunger and rotor in this manner, it is possible to reciprocate the plunger at a relatively slow speed, thus avoiding the necessity for a much more rapid propelling of said plunger, which would tend to injure the pieces when they are ejected from the pockets 33.

The gearing by which the stick conveying and transfer mechanism is operated in intermittent timed relation to the like operation of the wrapping drum to which the sticks are delivered, will now be described. The numerals used in connection with such gearing are the same as and correspond to the numerals used in the parent application.

118 (see Figure 7) indicates a continuously rotating shaft supported by the frame, driven in any convenient manner. Said shaft 118 is con-

nected by any familiar gearing, as by the familiar Geneva gearing indicated at 125 in Figure 7, to impart an intermittent timed movement to a horizontal shaft 36^a upon which is fixed the wrapping drum 36 (see Figures 1, 6 and 7). By such gearing the intermittent rotation of the wrapping drum 36 in the manner described is brought about.

126 indicates a horizontal shaft extending parallel to the intermittently rotating shaft 36^a and connected by gearing 127 at one end to the shaft 36^a and by miter gearing 128 to a transverse shaft 129 and gearing 130 to operate the intermittently rotated shaft 26 of the rotor 25 in the piece transfer casing 24 (see Figure 7).

On the intermittently rotating shaft 36^a is a sprocket 131 which, by a chain 132 indicated in dotted lines in Figure 1, is connected by a sprocket and chain to drive, in any familiar manner, the two feed rollers 133, 133^a which act to feed the piece wrapper strip 38 to and through the channel 39, and thence to the wrapping drum 36.

At the front of the machine on the forward end of the continuously rotating shaft 118 (see Figure 1) is mounted an eccentric mechanism 139 connected to a transfer bar 47^a by link 47^b. The plunger 35 which operates to transfer the pieces A from the casing 24 to the wrapping drum 36 is fixed to the top of one arm 35^x of a rocker member 140 mounted on a stud shaft 141 fixed to the frame (see Figures 1, 5 and 6). Said rocker member is connected by a link 142 to the eccentric 139. By this mechanism the transfer bar 47^a is operated in unison with the reciprocating movement of the plunger 35 so as to transfer the pieces A from the casing 24 to the wrapping drum in timed relation to the removal of said piece when partially wrapped, by the transfer bar 47^a.

An upper sealing iron 43 associated with the wrapping drum as shown in Figures 1 and 6 is carried at the upper end of an arm 143 which is fixed to the rocker member 140. The sealing iron is thus operated in timed unison with the plunger 35. A sealing iron 42 is mounted on a rock arm 144 pivoted on the frame at 144^a. 145 indicates a link yieldingly and pivotally connected to a fixed stud 146 on the rocker arm 140 at one end and pivotally connected by pin and slot 147 at the other end to operate the sealing iron 42 (see Figure 6). By this construction the sealing irons are brought to engagement with the margins of the wrappers for the pieces as hereinbefore described, with a yielding movement which permits them to remain in contact for a short length of time during the transfer of a piece from the casing 24 to the wrapping drum 36 by the reciprocating plunger 35.

While in describing the preferred embodiment of the invention it is shown as applied to the conveying of gum sticks, it will be understood that it is applicable for conveying sticks, pieces or other objects of any material. For the sake of brevity the term "sticks" will be used, where necessary, in the claims to refer to the articles which the machine is designed to convey.

I claim as my invention:

1. In a machine for wrapping sticks, means for intermittently feeding said sticks endwise, a casing disposed in a vertical plane at right angles to the plane of feed of said sticks and being provided with an inlet opening, a horizontal shelf spaced below said inlet opening, a rotary transfer disc intermittently rotatable upon a horizontal axis in said casing adapted to transfer a stick

delivered at said inlet opening to rest upon said shelf, aligned openings in the opposite walls of said casing in the plane of said horizontal shelf, and an intermittently operating plunger acting in line with said last named openings and in timed relation to the intermittent rotation of said transfer disc to discharge a piece from said shelf through one of said openings.

2. In a machine for wrapping sticks, means for intermittently feeding said sticks endwise, a casing disposed in a vertical plane at right angles to the plane of feed of said sticks and being provided with an inlet opening, a horizontal shelf spaced below said inlet opening, a rotary transfer disc intermittently rotatable upon a horizontal axis in said casing adapted to transfer a stick delivered at said inlet opening to rest upon said shelf, said rotary transfer disc being provided with arcuately spaced, upwardly and rearwardly opening pockets adapted to receive said pieces in succession, a spring-controlled gate providing a forward wall of said feed means, said disc having arcuate fingers extending in the direction of its rotation, means carried by said fingers adapted to swing said gate to permit a piece to be carried away by one of said pockets, and said arcuate fingers in succession being adapted to arrest the next succeeding piece and with said gate retain it until the next succeeding pocket is brought to position below it.

3. In combination, a casing, means providing a discharge chute opening into said casing including a spring-controlled gate normally providing the bottom part of the forward wall of said chute, a disc rotatably mounted on a horizontal axis, said disc being provided with a plurality of like, equally spaced pockets inclined rearwardly with respect to the direction of rotation of said disc, said disc being intermittently rotatable to bring a pocket below said chute, a shelf fixed in said casing and spaced below said chute, means carried by said disc adapted to support a stick in said chute until a pocket has been brought to position to receive it, and means intermediate said last named means and said gate adapted to swing said gate out of the way of a piece when it has dropped into said pocket.

4. In combination, a casing, means providing a vertical discharge chute opening into said casing, including a spring-controlled gate normally providing its front wall at its discharge end, an intermittently rotatable member on a horizontal axis in said casing provided with a plurality of like, equally spaced pockets inclined rearwardly to the direction of said rotation, a like number of equally spaced arcuate fingers traveling in a path radially beyond the path of said pockets, each finger presenting a stop to arrest the feed of said sticks after a stick drops into a pocket and to support the following stick until the next succeeding pocket is brought to position below said chute, and interacting means between said gate and said fingers adapted to swing said gate away from a supported stick when said next succeeding pocket is brought below said chute.

5. In combination, a casing, means providing a vertical discharge chute opening into said casing, including a spring-controlled gate normally providing its front wall at its discharge end, an intermittently rotatable member on a horizontal axis in said casing provided with a plurality of like, equally spaced pockets inclined rearwardly to the direction of said rotation, a like number of equally spaced arcuate fingers traveling in a path radially beyond the path of said pockets,

each finger presenting a stop to arrest the feed of said sticks after a stick drops into a pocket and to support the following stick until the next succeeding pocket is brought to position below said chute, interacting means between said gate and said fingers adapted to swing said gate away from a supported stick when said next succeeding pocket is brought below said chute, a fixed horizontal shelf below said chute adapted to receive a piece in the intermittent rotation of said disc, and means for ejecting said piece laterally from said shelf and said casing.

6. In combination, a casing, means providing a vertical discharge chute opening into said casing and adapted to discharge pieces lengthwise into said casing, a fixed shelf spaced below said discharge chute, an intermittently rotatable disc on a horizontal axis provided with a plurality of like, equally spaced pockets inclined rearwardly to the direction of rotation of said disc, said pockets being arcuately spaced to deliver a piece to said shelf when a following piece is discharged from said chute, said chute having a forwardly movable gate at its bottom end, means intermediate said disc and said gate adapted to release a piece when a pocket is below said chute, stops on said disc each extending between successive pockets adapted to retain said sticks in said chute until a pocket has come to rest therebelow, and a reciprocable plunger timed to discharge a piece on said shelf from said casing in an interim of the intermittent movement of said disc.

7. In combination, a casing, means providing a vertical discharge chute opening into said casing to discharge pieces lengthwise thereto, a fixed shelf in said casing spaced below said discharge chute, an intermittently rotatable member on a horizontal axis provided with a plurality of like, equally spaced pockets movable in succession through an angle of approximately ninety degrees from said discharge chute to said shelf, devices movable with said rotatable member bridging the spaces between said pockets adapted to retain said pieces in said chute until a pocket has been brought to position therebelow when a piece is released to said pocket in upright lengthwise position and the next following device stops further feed of the next piece above, and reciprocable means in line with said shelf moving in timed relation with said rotatable member and transversely of its plane of rotation adapted to discharge a piece in sidewise position from said shelf and casing in an interval of the intermittent movement of said rotating member.

8. In combination, a casing, means providing a vertical chute for discharging pieces lengthwise into said casing, a fixed shelf in said casing spaced below said discharge chute, an intermittently rotatable member on a horizontal axis provided with a plurality of like, equally spaced pockets movable in succession through an angle of approximately ninety degrees from said discharge chute to said shelf, and with a like number of arcuate fingers bridging the spaces between said pockets to retain said pieces in said chute until a pocket has been brought to a position therebelow and somewhat forward thereof, with the next succeeding finger arresting further discharge from said chute, and reciprocable means in line with said shelf movable transversely of said casing in timed relation with said rotatable member and transversely of its plane of rotation adapted to discharge a piece in sidewise position from said shelf and casing

in an interval of the intermittent movement of said rotating member.

9. In combination, a casing, means providing a vertical discharge chute opening into said casing to discharge pieces lengthwise thereto, an intermittently rotatable member on a horizontal axis provided with a plurality of like, equally spaced pockets movable in succession from said discharge chute, devices movable with said rotatable member bridging the spaces between said pockets adapted to retain said pieces in said chute until a pocket has been brought to position therebelow when a piece is released to said pocket and the next following device stops further feed of the next piece above, the retaining surfaces of said bridging devices being curved inwardly of said rotatable member adjacent each of said pockets so as to reduce the shock of the drop of a piece into the latter but to render said pockets relatively shallow, a fixed shelf spaced below said discharge chute adapted to support each piece in horizontal position when it comes to rest thereon, and reciprocable means operating in line with said shelf adapted to discharge such piece in sidewise position from said shelf and casing.

10. In combination, a vertical magazine including a spring-controlled gate normally providing its front wall at its discharge end, an intermittently rotatable member on a horizontal axis below said magazine, provided with a plurality of like, equally spaced pockets adapted to be moved successively into position below said magazine and adapted to receive sticks in upright position from said magazine, a fixed horizontal shelf in the path of movement of the sticks spaced below said magazine and adapted to support said sticks when they have reached a substantially horizontal position, means carried by said rotatable member for positively opening said gate to release said stick from the front of the magazine, and means operating in timed relation with said rotatable member for ejecting a stick from said shelf and said pockets.

11. In combination, a casing, a vertical discharge for delivering elongated pieces successively into said casing in upright position, a gate yieldably mounted at the discharge end of said chute and normally forming its front wall, an intermittently rotatable transfer member on a horizontal axis in said casing provided with a plurality of like, equally spaced pockets adapted to receive pieces from said chute in upright position, means carried by said rotatable member for positively opening said gate to release each piece from the front of said chute after it has been deposited in said pocket, and means for ejecting a piece from said pockets and said casing when said pockets have reached a predetermined position.

12. In combination, a casing, an upright discharge chute to discharge pieces into said casing, an intermittently rotatable member on a horizontal axis provided with a plurality of like, equally spaced pockets movable successively beneath said discharge chute to receive a piece therefrom, retarding devices movable with said rotatable member bridging the spaces between said pockets beyond the path of said pockets, adapted to retain said pieces in said chute until a pocket has been brought to receiving position therebelow, when a piece is released to said pocket and the next following retarding device stops further feed of the next piece above, a reciprocating plunger movable in timed relation with said

rotatable member and transversely of the plane of rotation of the latter for ejecting pieces successively from said pockets and from said casing, said rotatable member also having an arcuate slot extending circumferentially thereof adjacent each of said pockets and radially inwardly of said retarding devices so as to permit said rotatable member to resume rotation while said plunger is being withdrawn from each successive pocket.

13. In combination, a casing, an upright discharge chute to discharge pieces into said casing, an intermittently rotatable member on a horizontal axis provided with a plurality of like, equally spaced pockets movable successively beneath said discharge chute to receive a piece therefrom, a like number of equally spaced arcuate fingers extending in the direction of rotation of said rotatable member and traveling in a path radially beyond the path of said pockets, each of said fingers terminating above the proximate side of its respective pockets so as to retain said pieces in said chute until the succeeding pocket has been brought to position for receiving a piece from said chute, a reciprocating plunger movable transversely of the plane of rotation of said rotatable member in timed relation with said intermittently rotatable member for discharging said pieces successively from said pockets and said casing after said pieces have been carried to a point below said discharge chute, said arcuate fingers being arranged to permit said rotatable member to resume its rotation before said plunger is fully withdrawn from each successive pocket.

14. In a machine for wrapping elongated sticks, a casing, a vertically disposed chute for feeding said sticks into said casing, a rotary transfer disk intermittently rotatable upon a horizontal axis in said casing and having a plurality of like equally spaced pockets in its periphery adapted to receive successive sticks from said chute in upright endwise position, and upon rotation of said disk to move said sticks into a predetermined substantially horizontal position in said casing, said casing also having aligned openings in its side walls registering with the said predetermined horizontal position of said sticks, a rotary receiving disk disposed to one side of said casing and intermittently rotatable in timed relation with said transfer disk on an axis disposed at right angles to the latter, said receiving disk having a plurality of like equally spaced pockets in its periphery adapted to be successively positioned in alignment with the openings in said casing, and an intermittently operated plunger acting in line with said openings in said casing and acting in an interval of the intermittent rotation of said transfer disk and said receiving disk, to discharge the sticks successively from said casing and deposit them in horizontal sidewise position in the pockets of said receiving disk.

15. In a machine for wrapping elongated sticks, a casing, a vertically disposed chute for feeding said sticks into said casing, a horizontal shelf spaced below said chute, a rotary transfer disk intermittently rotatable upon a horizontal axis in said casing and having a plurality of like equally spaced pockets in its periphery adapted to receive successive sticks from said chute in upright endwise position, and upon rotation of said disk to move said sticks so as to rest upon said shelf in a substantially horizontal position, said casing also having aligned openings in its side walls registering with said shelf, a rotary receiving disk disposed to one side of said casing and intermittently rotatable in timed relation with said transfer disk on an axis disposed at

right angles to the latter, said receiving disk having a plurality of like equally spaced pockets in its periphery adapted to be successively positioned in alignment with the openings in said casing, and an intermittently operated plunger acting in line with said openings in said casing and acting in an interval of the intermittent ro-

tation of said transfer disk and said receiving disk, to discharge the sticks successively along said shelf and from said casing and deposit them in horizontal sidewise position in the pockets of said receiving disk.

LAWRENCE J. SALADIN.

CERTIFICATE OF CORRECTION.

Patent No. 2,351,838.

June 20, 1944.

LAWRENCE J. SALADIN.

It is hereby certified that error appears in the printed specification of the above numbered patent requiring correction as follows: Page 4, first column, line 7, claim 9, after the word "chute" and before the comma insert --to said shelf--; and that the said Letters Patent should be read with this correction therein that the same may conform to the record of the case in the Patent Office.

Signed and sealed this 15th day of August, A. D. 1944.
